Primary Examiner — Cynthia Ramirez(74) *Attorney, Agent, or Firm* — Cahn & Samuels, LLP(57) **CLAIM**

The ornamental design for a foldable tailgate ramp, as shown and described.

DESCRIPTION

FIG. 1 is a perspective view of a foldable tailgate ramp showing my new design;

FIG. 2 is a top plan view thereof;

FIG. 3 is a front elevational view thereof;

FIG. 4 is a rear elevation view thereof;

FIG. 5 is a right side elevational view thereof;

FIG. 6 left side elevational view thereof;

FIG. 7 is a bottom plan view thereof;

FIG. 8 is a perspective view of the foldable tailgate ramp in an unfolded position of use;

FIG. 9 is a perspective view of the foldable tailgate ramp in a partially folded position of use; and,

FIG. 10 is a perspective view of the foldable tailgate ramp in a completely folded position or use.

The broken lines showing a truck in FIGS. 8 through 10 are for the purpose of illustrating environmental structure and form no part of the claimed design.
